DESIGN FOR A FISHING REEL

Raney R. Allen, Dayton, Ohio

Application May 16, 1945, Serial No. 119,562

Term of patent 3½ years

(Cl. D31—4)

To all whom it may concern:

Be it known that I, Raney R. Allen, a citizen of the United States, residing at Dayton, in the county of Montgomery and State of Ohio, have invented a new, original, and ornamental Design for Fishing Reel, of which the following is a specification, reference being had to the accompanying drawing, forming a part thereof.

Figure 1 is a side elevational view of a fishing reel, showing my new design.

Figure 2 is an end elevational view of the reel, as viewed from the right of Figure 1.

Figure 3 is a top plan view looking down upon Figure 1.

Figure 4 is an end elevational view, as viewed from the left of Figure 1.

Figure 5 is a cross sectional view, taken substantially on the line 5—5 of Figure 1.

I claim:

The ornamental design for a fishing reel, as shown.

RANEY R. ALLEN.
